UNITED STATES PATENT OFFICE.

WILLIAM J. DE WITT, OF AUBURN, NEW YORK, ASSIGNOR TO THE SHOE FORM CO., INC., OF AUBURN, NEW YORK, A CORPORATION OF NEW YORK.

EXPANSIBLE SHOE FORM.

Application filed July 10, 1928. Serial No. 291,630.

This invention relates to an expandible shoe form designed to keep footwear plumped out or free from wrinkles, and is preferably made of celluloid or other 5 silent thin-walled material by a process such as is disclosed in my Patent No. 1,585,284, dated May 18, 1926. It will be noted, however, that so far as the present invention is concerned, the process by which the shoe 10 form to which this invention is directed is made, is immaterial. This invention is an improvement on the construction disclosed in my Patent No. 1,646,016, dated October 18, 1927, differing therefrom in certain 15 tails of construction as will be pointed out hereinbelow.

The primary object of this invention is to provide an expandible shoe form which is adapted to exert lateral pressure against the 20 side of the shoe, such pressure being yieldably applied to the form through a resilient thrust bar which bears against the heel counter of the shoe when the form is in place. A further object of the invention is 25 to provide a shoe form with a thrust bar so located and connected to the form that the latter can be inserted in a shoe quickly and easily by manipulation of the thrust bar alone.

30 Other objects of the invention will appear from a consideration of the following specification, taken in connection with the drawings, in which

Fig. 1 is a bottom plan view of a shoe 35 form embodying one form of this invention;

Figs. 2 and 3 are views similar to Fig. 1 of shoe forms embodying other forms of this invention; and

Fig. 4 is a sectional view taken along the 40 line 4—4 of Fig. 1.

The form designated in the drawings by the reference numeral 10 is a hollow, thin-walled member or shell including side walls 11 and 12 which terminate at the lower edges 45 in flanges 13, 14. These flanges, which may be integrally connected as shown in the drawing, are in the same plane so that when the form is positioned in a shoe the flanges rest upon the inner sole thereof. After the 50 form 10 has been positioned in a shoe the lower edges of the side walls 11 and 12 are expanded in order to fill out the toe of the

shoe and hold the material thereof smooth and free from wrinkles. In the present invention this function is performed by expanding means carried by the form and actuated by a resilient thrust bar as will be hereinbelow set forth.

In the embodiment shown in Fig. 1 the walls 11, 12 are expanded by means which include a pair of flat bars 15. The ends of each bar rest upon the flanges 13, 14 and the forward end of each bar is pivotally attached to one of the flanges by a rivet 16 set to permit a pivotal movement of the bar. 65 The rearward end of each bar is pivotally and slidably attached to the flange opposite that to which its forward end is pivoted by means of an arcuate slot 18 and a rivet 20, the head 21 of which rests against the under 70 face of the flange. The dimensions of the rivets and slots are such that the shanks of the rivets travel freely in the slots 18.

As shown in Fig. 1, one bar 15 overlies the other bar and each has a central slot 23 through which slots extend a rivet 24 carried at the inner end of a thrust bar 25 by which rivet the thrust bar 25 is pivotally and slidably attached to the cross bars 15. The thrust bar 25 is of resilient material, preferably of wire, and its inner end is formed into a loop 26 which surrounds loosely the shank 27 of the rivet 24. Thus the form may pivot laterally around the rivet 24 in a plane parallel to those of the bars 15 but, 85 owing to the fact that the loop 26 of the bar rests on the surface of the upper cross bar 15, it is held against swinging on the thrust bar 25 in another direction and can be held positively in any desired plane by the thrust 90 bar 25. Consequently it is not necessary to grasp the form and insert it in the shoe, but it can be so inserted by a manipulation of the thrust bar alone. The outer end of the bar 25 is provided with a loop 28 which, 95 when the form is in a shoe, rests against the heel counter.

The form 10 is first inserted in the shoe and then the thrust bar 25 is arched out of its normal position until the loop 28 can 100 be inserted in the shoe against the heel counter. The bar 25 is then released and, tending to return to its normal position, presses the loop 28 against the heel counter and through

the cross bars 15 forces the form 10 into the toe of the shoe. When the form reaches the limit of forward movement the bars 15 swing on the pivots 16 while the rivets 20 travel in the slots 18, thus expanding the side walls 11, 12. Should one side wall reach its outer limit of movement before the other, the rivet 24 will travel in the slot 23 of the stationary bar until the toe of the shoe is 10 fully plumped out. The thrust bar 25 yieldingly holds the form in this position.

The embodiment shown in Fig. 2 differs from that previously described in the form of expanding means, only a single cross bar 15 30 being provided. This cross bar is pivoted by a rivet 31 to a flange of one side wall and the other end of the cross bar 30 is provided with a rivet 33, the shank of which is passed through a slot 34 formed in the flange 20 of the other side wall. The thrust bar 25 is pivotally secured to the cross bar 30 intermediate its ends by a rivet 35. The thrust bar 25 is substantially the same as the one previously described, and the shank of the rivet 35 passes through a loop formed at the 25 inner end of the form. The thrust bar and form are thus connected in substantially the manner previously described, the form moving laterally of the bar in a plane parallel 30 to that of the bar 30 but being prevented by the contact of the loop 26 with the upper surface of the cross bar 30 from swinging relatively to the bar in other directions. In order to check the pivotal movement of the cross bar 30 the outer edge of the slot 34 is 35 provided with a plurality of shallow notches 38 which receive the shank of the rivet 33. As pointed out above, the shoe form is inserted in the toe of the shoe by manipulation 40 of the thrust bar 25, and the thrust bar 25, after properly seating the form, is arched to allow the entry of the loop 28. The pressure created by the arched bar causes the cross bar 30 to pivot on its rivet 31, the 45 other end of the cross bar swinging in the slot 34. The shank of the rivet 33 thus travels from one notch 38 to another until the form has been expanded sufficiently to place the shoe in its proper condition. The engagement of the rivet 33 with the last notch 38 it enters on the pivotal movement of the cross bar 30 acts to hold the cross bar in that 50 position, thus supplementing the action of the thrust bar 25. The notches 38 may be omitted if desired and the cross bar 30 held in position solely by the action of the thrust bar 25.

In the Fig. 3 embodiment the form is provided with expanding means including two 60 cross bars 40 and 41. These cross bars overlap each other as in the embodiment shown in Fig. 1 but only the under cross bar 40 is provided with a slot 42. The forward ends of the cross bars are pivotally attached to 65 the flanges 13, 14 of the side walls by rivets

43 and the rearward ends of the cross bars are pivotally and slidably attached to the flanges by rivets 44 through slots 18. The thrust bar 25 is pivotally secured to the cross bars 40, 41 by a rivet 45 which is 70 passed through the loop 26 and the slot 42 in the cross bar 40 and is carried by the cross bar 41. The slot 42 permits the rivet 45 to slide in the cross bar 40 when the form is set in the shoe as previously described. The rivet 45 permits the form 10 to swing relative to the thrust bar 25 in a plane parallel to those of the cross bars 40 and 41 but the loop 26 resting on the cross bar 41 prevents the form from swinging relative to the bar 80 in other directions.

The embodiments here shown have been described as including certain elements such as, for example, rivets, loops and slots, but it will be understood that equivalents of 85 these elements may be employed and the specific description thereof is merely by way of illustration and not of limitation. While certain embodiments of this invention have been shown and described, I do not wish to 90 be limited thereto since others might be made without departing from the spirit and scope of the invention as set forth in the following claims.

I claim:

1. A shoe form having expandible side walls and including means for expanding the side walls, such means being pivoted to one side wall and slidably connected to the other side wall in combination with a thrust 100 bar for actuating such means, and means pivotally connecting the thrust bar to such expanding means whereby said form can swing relative to the thrust bar in one plane only.

2. A shoe form having expandible side walls and including means for expanding the side walls, such means being pivoted to one side wall and slidably connected to the other side wall in combination with a thrust bar for actuating such means, and means so connecting said thrust bar to said expanding means that the form can be inserted in the toe of a shoe by manipulation of the thrust bar alone.

3. A shoe form having expandible side walls flanged at the lower edges thereof, and including means attached to the flanges of said walls and slideable at one end relative to one flange for expanding the walls in combination with a thrust bar for actuating such means, and means for pivotally connecting the thrust bar to such expanding means whereby said form can swing relative to the thrust bar in one plane only.

4. A shoe form having expandible side walls flanged at the lower edges thereof and including means pivotally attached to the flange of one side wall and pivotally and slidably attached to the flange of the other side wall, in combination with a thrust bar for actuating such means, and means pivot-

ally connecting the thrust bar to said expanding means whereby said form can swing relative to the thrust bar in one plane only.

5. A shoe form having expandible side walls flanged at the lower edges thereof and including means for expanding said side walls, such means comprising a cross bar pivotally attached to the flange of one side wall and pivotally and slidably attached to the flange of the other side wall in combination with a thrust bar for actuating such expanding means and means pivotally connecting said thrust bar to said cross bar whereby said form can swing relative to the thrust bar in one plane only.

6. A shoe form having expandible side walls flanged at the lower edges thereof and including means for expanding said side walls, such means comprising a cross bar pivotally attached to the flange of one side wall and pivotally and slidably attached to the flange of the other side wall in combination with a thrust bar for actuating such expanding means and means pivotally and slidably connecting said thrust bar to said cross bar whereby said bars can slide and swing relative to each other and said form can swing relative to said thrust bar in one plane only.

30 7. A shoe form having expandible side walls flanged at the lower edges thereof and including means for expanding said side walls, such means comprising a cross bar pivotally attached at its forward end to the flange of one side wall and pivotally and slidably attached at its rearward end to the flange of the other side wall and having a slot therein in combination with a thrust bar for actuating such expanding means and having a loop at its forward end and means passed through said loop and said slot for pivotally and slidably securing said thrust bar to said cross bar.

8. A shoe form having expandible side walls flanged at the lower edges thereof and including means for expanding said side walls, such means comprising a cross bar pivotally attached at its forward end to the flange of one side wall and pivotally and slidably attached at its rearward end to the flange of the other side wall and having a slot therein in combination with a thrust bar for actuating such expanding means and having a loop at its forward end and a rivet through said loop and said slot for pivotally and slidably securing said thrust bar to said cross bar.

9. A shoe form having expandible side walls flanged at the lower edges thereof and including means for expanding said side walls, such means comprising a pair of cross bars overlapping each other, the forward end of one bar being pivotally attached to the flange of one side wall and the rearward end being pivotally and slidably attached to

the flange of the other side wall and the forward end of the other bar being pivotally attached to the flange to which the rearward end of the first bar is attached and the rearward end of the other bar being pivotally and slidably attached to the flange to which the forward end of the first bar is attached, the overlapping portions of said bars being slotted in combination with a thrust bar, and means pivotally and slidably securing the forward end of the thrust bar to the overlapping portions of said cross bars.

10. A shoe form having expandible side walls flanged at the lower edges thereof and including means for expanding said side walls, such means comprising a pair of cross bars overlapping each other, the forward end of one bar being pivotally attached to the flange of one side wall and the rearward end being pivotally and slidably attached to the flange of the other side wall and the forward end of the other bar being pivotally attached to the flange to which the rearward end of the first bar is attached and the rearward end of the other bar being pivotally and slidably attached to the flange to which the forward end of the first bar is attached, the overlapping portions of said bars being slotted in combination with a thrust bar, and means pivotally and slidably securing the forward end of the thrust bar to said cross bars, such securing means engaging the slots in the overlapping portions of the cross bars.

11. A shoe form having expandible side walls flanged at the lower edges thereof and including means for expanding said side walls, such means comprising a pair of cross bars overlapping each other, the forward end of one bar being pivotally attached to the flange of one side wall and the rearward end being pivotally and slidably attached to the flange of the other side wall and the forward end of the other bar being pivotally attached to the flange to which the rearward end of the first bar is attached and the rearward end of the other bar being pivotally and slidably attached to the flange to which the forward end of the first bar is attached, the overlapping portions of said bars being slotted in combination with a thrust bar having a loop in the forward end thereof, and means passed through said loop and through the slots in the overlapping portions of the cross bars for pivotally and slidably securing the thrust bar to the cross bars.

12. A shoe form having expandible side walls flanged at the lower edges thereof and including means for expanding said side walls, such means comprising a pair of cross bars overlapping each other, the forward end of one bar being pivotally attached to the flange of one side wall and the rearward end being pivotally and slidably attached to the flange of the other side wall and the forward end of the other bar being pivotally attached

to the flange to which the rearward end of the first bar is attached and the rearward end of the other bar being pivotally and slidably attached to the flange to which the forward end of the first bar is attached, the overlapping portions of said bars being slotted in combination with a thrust bar having a loop

in the forward end thereof and a rivet through said loop and through the slots in the cross bars for pivotally and slidably securing the thrust bar to the cross bars. 10

Signed by me at Auburn, N. Y., this 6th day of July, 1928.

WILLIAM J. DE WITT.
